UNITED STATES PATENT OFFICE.

UNION DODD, OF SOUTH BEND, ASSIGNOR OF ONE-HALF TO WILLIAM HOLLAND, OF PLYMOUTH, INDIANA.

BRIDGE-GATE.

SPECIFICATION forming part of Letters Patent No. 336,843, dated February 23, 1886.

Application filed November 4, 1885. Serial No. 181,844. (No model.)

To all whom it may concern:

Be it known that I, UNION DODD, a citizen of the United States, residing at South Bend, in the county of St. Joseph and State of Indiana, have invented certain new and useful Improvements in Bridge-Gates, of which the following is a specification, to wit:

This invention relates to bridge-gates; and it consists in certain peculiarities of the construction and arrangement of the same, substantially as will be hereinafter more fully set forth and claimed.

In order to enable others skilled in the art to which my invention pertains to make and use the same, I will now proceed to describe its construction and operation, referring to the accompanying drawings, in which—

Figure 1 is a front view of a bridge-approach and my gate, and Fig. 2 is a side elevation of the abutting ends of the bridge and its approach. Fig. 3 is a detail view of the spring.

a represents a swing draw-bridge of the usual or any desired form, and *a'* the approach or abutment with which the bridge connects when closed. Upon the approach are placed the posts *b*, one at each side, and on one of them are pivoted two long cross-bars, *b'*, which are connected at intervals by pickets *b''*, these pickets being connected to the cross-bars by a single pivotal pin or bolt, as shown. One of the cross-bars *b'* is extended in rear of its post, and is provided with a rod or link, *b''*, which extends down alongside of the abutment, and is connected to a lever, *c*, the opposite end of which is pivoted upon the face of the abutment, as in Fig. 1. The free end of this lever is confined in a guide, *c'*, in which it is free to move, as represented. Upon a suitable support, *d*, on the abutment is placed a flat spring, *d'*, of concavo-convex form, the ends of which

are confined by bolts *d''*, and one or both ends are formed with slots *d'''* to allow of the expansion of the spring when compressed. A short rod or bar, *e*, connects the center of the spring *d'* with the lever *c*, and when it is necessary an auxiliary spiral spring, *e'*, is placed around the rod beneath the mainspring to strengthen it.

In use, when the bridge is closed, the end passing over the mainspring compresses it, and by means of its connecting-rod depresses the lever *c*, the free end of which at once draws down the rear projecting end of the cross-bar and elevates the gate, the whole folding up, as seen by dotted lines in Fig. 1, as it is elevated. As the bridge is opened, the gate is allowed to fall and protects the end of the abutment, as will be at once understood.

Having thus fully described my invention, what I claim as new, and desire to secure by Letters Patent, is—

1. The combination, with a swing-bridge, of a compression-spring on the abutment, a lever connected to said spring and also to the gate, and a gate composed of parallel bars hinged at one end and connected by pickets pivoted thereon, substantially as and for the purpose set forth.

2. The combination, with the bridge *a*, of the gate *b'* *b''*, the connecting-rod *b''*, lever *c*, springs *d'* *e'*, and rod *e*, all constructed and arranged to operate substantially as and for the purpose set forth.

In testimony whereof I affix my signature in presence of two witnesses.

UNION DODD.
